Primary Examiner — Mark A Goodwin

(57) **CLAIM**

The ornamental design for a filter housing and pipework for an engine, as shown and described.

DESCRIPTION

FIG. 1 is a perspective view of a filter housing and pipework for an engine showing our new design;

FIG. 2 is a rear view thereof;

FIG. 3 is a left side view thereof; and,

FIG. 4 is a right side view thereof.

The claimed design is indicated by the relatively dark portions in the figures. The relatively light portions form no part of the claimed design.

1 Claim, 4 Drawing Sheets
